United States Patent Office

Des. 204,329
Patented Apr. 5, 1966

204,329

MACHINE FOR VALIDATING TICKETS

Leonard Simmons, 34 Hewlett Lane, Flower Hill,
Port Washington, N.Y.

Filed June 8, 1964, Ser. No. 80,310

Term of patent 3½ years

(Cl. D64—11)

FIG. 1

FIG.2

FIG.3

FIG.6

FIG.4

FIG.5

FIG. 1 is a perspective view in elevation of a machine for validating tickets showing my new design;

FIG. 2 is a plan view;

FIG. 3 is a front view;

FIGURE 4 is a side elevational view taken from the right of FIGURE 3; FIGURE 5 is a side elevational view as seen from the left hand side of FIGURE 3 and, FIGURE 6 is a rear elevational view of the article.

The dotted line showing of printed matter is for illustrative purposes only.

I claim:

The ornamental design for a machine for validating tickets, substantially as shown and described.
